UNITED STATES PATENT OFFICE

146,506

DESIGN FOR A NIGHTGOWN

Mary O. Kenny, San Bernardino, Calif.

Application April 23, 1946, Serial No. 128,879

Term of patent 14 years

(Cl. D3—26)

To all whom it may concern:

Be it known that I, Mary O. Kenny, a citizen of the United States, residing at San Bernardino, in the county of San Bernardino and State of California, have invented a new, original, and ornamental Design for Nightgown, of which the following is a specification, reference being had to the accompanying drawing, forming part thereof.

The drawing illustrates a nightgown embodying my new design in which Fig. 1 is the front view and Fig. 2 is the rear view.

I claim:

The ornamental design for a nightgown, as shown.

MARY O. KENNY.
